KNITTING MECHANISM

Edward Kinsella, John Gordon Pratt, and Bernard Kelsall, Spondon, near Derby, England, assignors to Celanese Corporation of America, a corporation of Delaware

Application October 26, 1932, Serial No. 639,635
In Great Britain November 3, 1931

1 Claim. (Cl. 66—86)

This invention relates to the production of textile fabrics, and more particularly to the production of knitted fabrics on warp knitting machines.

5 The object of the invention is to improve warp knitting machines with the object of greatly increasing their rate of working and smoothness of operation, and rendering them capable of knitting fabrics of better and more uniform 10 quality.

It has been found that a much improved rate 15 of operation can be effected by the provision of an improved form of machine frame which is of rigid construction, so that it does not depend upon secure anchoring in position to resist vibration. According to the invention a frame for warp knitting machines comprises a plurality of vertical frame members carrying the bearings for the cam and rocker arm shafts of the machine, said vertical members being connected together by means of stiffening members firmly secured to the vertical members so as to form a rigid structure of box or girder-like form. Preferably said transverse members are each in 20 one piece and attached to each frame member at at least two points with large facings, and the vertical frames of triangulated structure, rigid against distortion in their own plane. The transverse members themselves constitute girders of extreme rigidity.

Thus for example, the vertical frames of the machine may be connected together by means of plate members with stiffening ribs or flanges, adapted to form a box construction for the base 35 of the machine. The lower half of the machine is formed at the front and rear of stiffening plates of rigid character extending between pairs of vertical frames. The top edges of said stiffening plates may also be connected by horizontal 40 stiffening plates lying below the cam mechanism. In this manner, the base of the machine consists of a box construction with an open bottom, the cross members of the vertical frames serving to tie the edges of the open bottom 45 together in a rigid manner.

The stiffening plates are conveniently of cast form. For the sake of lightness, parts of the plates may be cut away where possible, more particularly where diagonal ribs are employed. 50 Thus, by providing double flanges running diagonally across the members and by omitting the intermediate triangular portions of the web, a stiffening plate of X form may be produced for the purpose, and the cutting away of the web 55 in this manner may be carried even to such an

extent as to form a stiffening plate of open X character, though preferably part of the web, flanged if necessary, should be left along one side of the member, i. e. the upper side.

A similar stiffening member may be employed 5 to connect the upper parts of the vertical frames as well as the bases, though it is preferred that such a stiffening member should take up as little space as possible in order not to interfere with the working parts of the knitting machine or to 10 hinder the operative in reaching such parts.

The invention is of particular advantage in connection with the invention described in U. S. Patent No. 1,981,511. This specification describes the use of a particular form of cam 15 mechanism for carrying out the lapping motion of the guide bars of a warp knitting machine at high speeds.

The invention will now be described in greater detail with reference to the accompanying drawings, but it is to be understood that this description is given by way of example only and is in no respect limitative.

Figures 1, 2 and 3 are front, side and rear elevations of part of a knitting machine frame 25 constructed in accordance with the present invention;

Figure 4 shows a detail of the frame shown in Figures 1 to 3;

Figure 5 is a side elevation in part section of 30 another form of warp knitting machine frame according to the invention;

Figure 6 is a part front view of Figure 5 with the front plates removed to show the rear plates; 35

Figure 7 is a detail of the frame construction shown in Figures 5 and 6.

Referring to Figures 1 to 4, the machine frame shown comprises a series of vertical frame members 10 of which two are shown in Figure 1 and three in Figure 3, the vertical frames 10 being connected together over their lower halves by means of girder sections, indicated at 12 at the front of the machine and at 13 at the rear of the machine shown in Figures 1 and 3 respectively.

The girder sections 12, 13 are of X form and identical in shape though differently positioned in front and rear of the machine, one being vertical and the other somewhat inclined. They 50 are cast in one piece, and comprise cross members 14 having flanges 15 and meeting at a boss 16 in the center which is heavily reinforced by ribs and flanges 17, and a horizontal member 18 across the top. 55

The girder sections are bolted to the machine frame at rectangular projecting bosses 20 shown in dotted lines in Figure 2, the bosses 20 being bored at 21 for the reception of the connecting bolts. The ends of the sections and the bosses are machined so as to fit accurately together and form large facings.

The sections 12, 13 not only firmly space the frames 10 but also by the triangulated structure 13 they form with the frames prevent endwise distortion of the frame under the action of the forces involved in driving the knitting mechanism. The whole base of the frame is thus adequately stiffened against deflection of vibration.

15 The upper parts 25 of the frames 10 are connected by means of girder sections 26 bolted on the projecting bosses 27 on the upper part of the frame 10. The section 26 is cast in one piece and is of the shape as shown in Figure 4 comprising 20 a curved web 28 perforated with vertical holes at 29 and provided with stiffening flanges 30. These members stiffen the upper portions of the frame 10 and resist endwise distortion of the frame above the part stiffened by the girders 12, 13.

25 The form of the frames 10 is clearly shown in Figure 2, wherein it will be seen that they comprise webs 35 flanged all round as at 36 and forming a triangulated structure which resists distortion of the frames in their own plane, so that in 30 conjunction with the stiffening afforded by the transverse sections 12, 13 and 26 the machine as a whole is extremely rigid and able to withstand distortion and vibration. The frames 10 carry bearings 37, 38, 39, 40 and 41 for the guide rocker 35 brackets, the needle rocker arms, the main cam shaft, the sinker rocker arms and the presser rocker arms respectively (see U. S. Patents Nos. 1,981,513 and 1,981,512).

On the upper part of the frame, secured to fac- 40 ings 45, 46 is a bracket 47 shown in dotted lines, carrying the warp beams 48 and bosses 49, 50, to which are pivoted tension bars over which the threads pass on their way to be knitted. (See U. S. Patent No. 2,014,530.) The frames 10 are of con- 45 siderable width at the part 110, so that the cantilever formed by the upper part of each frame does not deflect under the dead load of the warp beams, thread guides etc., and any unbalanced forces arising from the operation of the ma- 50 chine.

The bracket 53 shown in dotted lines carries the take-up device on which the fabric is collected after knitting. The caps for the bearings 37 to 41 are shown in dotted lines.

55 Each of the frames 10 is reinforced in front by means of a vertical member 55 whose section is clearly shown at 56, the vertical member 55 being removable, as well as the front girder section 12, in order that the bearings 41 may be 60 reached for assembly or removal of the presser bar shaft carried thereby, the shaft running in- teriorly of the assembled frame.

The frame shown in Figure 2 is an end frame, for which reason the bosses 20, 27 extend on the 65 far side of the frame only, and are therefore shown in dotted lines. On the intermediate frame these bosses extend on both sides of the frame shown in Figures 1 and 3. The end frame

10 in Figure 2 is provided with a boss 58 bored for the cam shaft of the warp feeding means de- 5 scribed in U. S. Patent No. 2,014,530. The frames 10 though relatively thin, form by their flanged construction in conjunction with the stiffening 55 afforded by the members 12, 13, 26 and 55 a sub- stantially vibrationless support for the knitting mechanism and operating gear.

In Figures 5 to 7, a frame construction of slight- 10 ly different kind is shown comprising vertical frames 60, each of which is connected to the ad- jacent frame by means of three plate-like mem- 15 bers 61, 62, 63. These plates are bolted by means of bolts 64 to square projecting bosses 65 on the frames 60. The plates 63 shown in Figure 5 and 15 also the plates 61 at the rear of the machine are provided with end flanges 67, and with ribs 68 extending diagonally across the plates and meet- 20 ing at a circular boss 69 at the center. The plates 61 and 63 are turned over at their upper 25 edges 71 and provided with flanges 72 engaging with the top plate 62 shown in Figure 7 on a slightly larger scale. The flanges and stiffening ribs of the plates 61, 63 give the plates a stiff, de- flection-resisting girder-like structure.

The top plate shown in Figure 7 consists of a plate 74, diagonal ribs 75 and flanges 76 at the edges, one of which is shown in section as at 77. This girder-like structure stiffens the frame against sideways distortion. The plates 62 are 30 of different length from the plates 61, 63, so that their ends do not coincide at the frame 60 but extend beyond the frames, thus increasing their strengthening effect on the machine structure 35 by breaking the joints occurring at the frames 60. The point of junction of two top plates is shown at 78 in dotted lines in Figure 6.

It will be seen that the plates 61, 62, 63 form a box-like structure for the base of the machine, the structure being open at the bottom. The low- 40 er edges of the box-like structure are tied together by cross members 80 on the lower part of the vertical frame 60. The vertical frame 60 comprises a web 81 shown in dotted lines in Figure 6 and flanges 82 extending all round. The frames 45 are provided with bearings as at 83 for the work- ing parts of the machine.

What we claim and desire to secure by Letters Patent is:—

A warp knitting machine frame comprising ver- 50 tical frame members extending from front to rear of the machine frame and transverse connecting members of deep X form, each extending vertically over the lower part of said vertical frame members so as to resist lateral rocking of said 55 vertical frames, bearings on said vertical frame members adapted to carry shafts of the knitting mechanism, removable stiffening elements in said vertical frames adapted to permit a shaft to be mounted interiorly of the vertical frames, up- 60 wardly extending portions of said vertical mem- bers, and transverse members of triangulated panel form connecting said upwardly extending portions together, the whole making a rigid struc- 65 ture of vibration-resistant character.

EDWARD KINSELLA.

JOHN GORDON PRATT.

BERNARD KELSALL.
